VARIABLE BAND-PASS FILTER CIRCUITS

James J. Lamb, West Hartford, Conn., assignor
to Radio Corporation of America, a corpora-
tion of Delaware

Application July 9, 1937, Serial No. 152,728

4 Claims. (Cl. 178—44)

This invention relates to variable band-pass filter circuits and has more particularly to do with a device having full-range superheterodyne selectivity in an intermediate frequency amplifier. The full-range of selectivity ideally desirable in radio superheterodyne receivers would embrace band-widths from the minimum required for carrier wave telegraph signals to the maximum required for high fidelity speech and music modulation. In practice this might mean a total effective band-width range of from 100 cycles to over 20 kilocycles. Furthermore, in order to cope with the wide variety of interference conditions encountered with the different types of signals, the selectivity should be continuously variable through this 200 to 1 range, and should also include the additional feature of ability to reject a particular interfering signal even within the band-width range for which the receiver may be adjusted, especially in carrier wave telegraph reception.

Accordingly, it is an object of my invention to provide a band-pass filter system for use in an intermediate frequency amplifier which shall be continuously variable in band-width from below 100 cycles to over 10 kilocycles.

It is another object of my invention to provide a system of the type suggested above wherein means are included for rejecting interfering signals within the band-width range for which the receiver may be adjusted.

In carrying out my invention I have found that the full-range encompassed may be covered in substantially three steps, each capable of giving continuously variable band-width between its minimum and maximum limits. These are from 100 cycles or less to approximately 3.5 kilocycles, from 3.5 to approximately 9 kilocycles, and from 9 kilocycles to over 20 kilocycles. In considering these band-widths it may be assumed that throughout the spread of each band at least 10% of the maximum response is obtainable at the upper and lower frequency limits respectively. Such an assumption is quite reasonable as has been shown in my paper entitled "Receiver selectivity characteristics" published in "Q. S. T.", May 1935.

For the highest selectivity range the familiar variable selectivity quartz crystal filter is used; for the medium range I prefer to use what has been termed a "Transfilter" unit in place of the quartz crystal; and for the broadest range variable selectivity interstage transformer coupling fulfills the job with the filter circuit by-passed or switched out.

The Transfilter unit has been described in my article entitled "A new I. F. coupling system for superhet receivers", published in the April 1937 issue of "Q. S. T." This Transfilter unit combines the properties of a transformer and an electric wave filter. Like the quartz filter it is electro-mechanical in nature. Also like the quartz crystal filter, it involves piezo-electric action. But the Transfilter is not entirely a piezo-electric device and should not be considered as such. Its construction includes a steel bar to determine the frequency of resonance, and this bar has mechanically coupled to it extremely small plates of Rochelle salt. This combination of a relatively large bar of steel and a very small piece of crystal is such that large variations in the characteristics of the crystal have negligible effect on the characteristics of the complete assembly. As an example of a Transfilter having suitable dimensions for use in the circuit arrangement presently to be described, it may be said that such a Transfilter comprises a steel rod somewhat less than $\frac{3}{4}$ " long and approximately $\frac{1}{16}$ " in diameter. Four small crystal plates each $\frac{1}{8}$ " square and 0.02" thick are secured to this rod near its center. Two of these plates are connected in parallel and used as the driver or input elements. The other two plates are also connected together and constitute the output elements. When an alternating potential of the proper frequency is applied to the plates the bar is set into resonant vibrations which react on the crystal to generate a counter-electromotive force.

Qualitatively the Transfilter displays the same electrical characteristics found in quartz resonance; that is, essentially capacitive reactance at most frequencies with a sudden deviation from this reactance at the frequency of resonance of the bar. Hence it may be used in bridge circuits in the same manner as a quartz filter. However, the Rochelle salt driver steel bar has somewhat higher mechanical damping with the result that the filter is not as sharp as quartz; hence the advantages of using such a filter in the intermediate band-width of selectivity. The Transfilter, on the other hand, provides much higher selectivity than is available with the use of audio tuned circuits.

The Transfilter unit itself as above described is well known in the art and I lay no claim to the invention of this particular unit since its uses were widely explored by W. G. Cady as shown by his article "The piezo-electric resonator" pub-

lished in "I. R. E.", April 1922 and covered by United States Patent No. 1,450,246.

The features of novelty of my invention are believed to be defined by the appended claims. 5 The invention itself, however, as to its structural details and mode of operation, will be best understood upon reference to the accompanying drawings when viewed in the light of the following description. In the drawings:

10 Figure 1 shows a circuit diagram of a super-heterodyne receiver embodying an intermediate frequency amplifier and a combination of filter systems which may be selectively used for varying the band-width;

15 Fig. 2 shows a selectivity curve appropriate to the operation of the circuit arrangements of Fig. 1;

Fig. 3 shows curves of total band-width obtainable by the operation of the circuit of Fig. 1;

20 Fig. 4 shows details of a modified arrangement of an impedance matching Transfilter;

Fig. 5 shows for purposes of comparison a variation from the circuit arrangements of Fig. 4;

Fig. 6 shows a selectivity curve appropriate to 25 the circuit arrangement of Fig. 4;

Fig. 7 shows total band-width curves for resistance variation;

Fig. 8 shows a modification of the invention in which a band-pass circuit is used comprising two

30 Transfilters in parallel, and Fig. 9 shows maximum and minimum selectivity curves in respect to the circuit arrangement of Fig. 8.

35 Referring first to Fig. 1, I show therein an illustrative embodiment of the invention which includes a first detector stage tube 1, a heterodyne oscillator 2, a first intermediate frequency amplifier 3, a second intermediate frequency amplifier 4, a second detector 5, and interconnecting circuit arrangements presently to be described in more detail. The transformer 6 coupling the antenna circuit or radio frequency amplifier to the first detector 1 may be of any conventional type. Transformers 7, 8 and 9 are preferably of the air-tuned, air-core type. The second detector 5 is preferably a double diode. The audio frequency amplifier is connected to the output leads 10.

40 The two intermediate frequency transformers 8 and 9 are adjusted for a relatively broad frequency characteristic to provide a fair amount of tolerance near resonance thereby to accommodate minor deviations in frequency of the several piezo-electric or Transfilter devices used.

45 As shown in the drawing, the first intermediate frequency stage is preceded by an arrangement of alternative filter circuits. For the band-width of sharpest selectivity the piezo-electric crystal 11 is switched into circuit between one terminal of the secondary of the transformer 7 and the adjustable coupling condenser 12. The switching arrangement includes a double-pole, triple-throw switch indicated generally at 13. The crystal 11 is connected in circuit with the switch arms if in the position shown. In the intermediate position of the switch arms a Transfilter unit 14 is substituted for the quartz crystal. The steel bar 15 of the Transfilter unit is grounded. In the third position of the switch 13 both the quartz crystal 11 and the Transfilter unit are cut out and tuning is obtained for the broadest selectivity band by merely short-circuiting the switch points 16.

50 The variable capacitor 17 in shunt with the secondary of the transformer 7 is used to control the band-width or selectivity. Another variable

5 capacitor 18 in opposition to the filter units controls the rejection of interfering signals. In varying the band-width by adjustment of the parallel tuned impedance as indicated in the diagram, maximum band-width (minimum selectivity) occurs with this circuit tuned to crystal resonance and decreasing band-width (increasing selectivity) occurs as the parallel tuned circuit becomes reactive on either side of resonance. With the impedance matching which this circuit 10 provides, the over-all carrier wave gain of the receiver is practically the same with the input circuit adjusted for "optimum" (medium high) selectivity as it is with the crystal shorted out and the input circuit adjusted for maximum 15 "straight" superhet gain. Either side of this point the over-all gain decreases slightly, both toward maximum band-width and toward extreme minimum band-width.

20 The Transfilter unit 14 is of fairly low impedance and accordingly cuts the gain of the input amplifier or first detector when fed directly from its anode 19. When the Transfilter is used by setting the switch 13 to its intermediate position, selectivity is varied by the same method as when 25 the crystal filter is used; that is, by variation of the parallel tuned impedance which constitutes the input to the divided circuit. Although the selectivity control condenser 11 settings are not exactly the same as for a quartz crystal filter of 30 corresponding frequency, minimum selectivity occurs with the input circuit resonant to the Transfilter frequency and increasing selectivity occurs as the input circuit is tuned either side of resonance. The resonance setting (maximum 35 band-width) comes at lower tuning capacitance with the Transfilter than with the crystal because the Transfilter capacitance to ground is apparently greater by as much as 10 micro-micro-farads. The adjustment is still well within the range of 40 the condenser, however.

Many of the details of the circuit arrangements shown in Fig. 1 are self-explanatory but in some respects they follow the teachings of my Patent No. 2,054,757, granted September 15, 1936, reference to which may be made for further explanation of these details.

45 The range of selectivity obtainable with the crystal filter circuit is shown by curve A in Fig. 2 as a maximum and by curve B when the crystal is adjusted for minimum selectivity. Between these two curves A and B a characteristic shading has been introduced for representing the band-width variation under different adjustments. A different shading has been used to 50 show the band-width variation under the different adjustments between a maximum selectivity limit C and a minimum selectivity limit D when the Transfilter is used. Curve E is for the transformer-coupled selectivity characteristic of the 55 intermediate frequency amplifier without either filter, that is, when the switch 13 is moved to the extreme right for short-circuiting the contact points 16.

60 It is interesting to note that the selectivity range with the Transfilter practically continues on from where the crystal range reaches its broadest. This is illustrated even more clearly by the total band-width curves of Fig. 3 which are plotted from the same experimental data as 65 used in plotting the curves of Fig. 2. The principal difference between the selectivity of the crystal filter at its broadest and the Transfilter at its sharpest is that the Transfilter selectivity characteristic is somewhat broader near reso- 70 75

nance, giving a slightly greater effective bandwidth.

Under practical working conditions the circuit arrangements of my invention as herein described have been shown to be well adapted for use either for carrier wave telegraph signals with slow-speed keying, as when maximum crystal filter selectivity is wanted and also for reception of speech and music signals under adverse interference conditions where the broadest bandwidth is required for high fidelity. Throughout this range the crystal filter also provides adjustable rejection or control of symmetry of the response characteristic for elimination of a particular interfering carrier even within the normal band-width range. On the other hand, the Transfilter selectivity range carries on from this point to a band-width sufficiently great for speech reception with entirely adequate fidelity. In fact, the Transfilter selectivity at its broadest is generally useful for broadcast program reception, providing fidelity fully as good as those customary with the average broadcast receiver.

This range is especially adapted to short-wave broadcast reception where it is desirable to constrict the frequency band of the receiver anyway because of the noise and adjacent-channel interference which is aggravated by the fading so characteristic of these frequencies. True high-fidelity reception is practically never feasible on the high-frequency bands, and considerable high-frequency attenuation is inevitably necessary. This is accomplished by the intermediate frequency band-width control with the Transfilter in much more satisfactory fashion than it can be obtained by an audio-frequency tone control with ordinary intermediate frequency selectivity. The intermediate frequency band-width control accomplishes the same effect of reducing the noise but does so without introducing the amplitude distortion which may occur with audio-frequency tone control. Furthermore, it does the job prior to the second detector and removes noise and adjacent-channel sideband components before they have a chance to intermodulate with the desired signal in the second detector to produce low-frequency audio components which cannot be removed by audio-frequency filtering subsequent to detection.

A matter of some importance in judging the relative merits of selective intermediate frequency circuits, in addition to their contribution of selectivity, is their effect on the over-all gain and effective sensitivity. In connection with crystal filters, for instance, there is considerable divergence of opinion as to whether this or that particular arrangement is the better in point of how little it reduces the gain of the receiver. In my experience, the impedance-matching crystal filter circuit of Fig. 1 has practically negligible effect on the carrier wave gain of the receiver as compared to the gain with the crystal shorted out and the circuit tuned to intermediate frequency resonance for "straight" superhet operation. This refers particularly to the carrier wave gain with the crystal filter circuit adjusted for optimum selectivity, at which adjustment the second-detector input (and the carrier wave beat-note output) is maximum. The gain is actually reduced at minimum selectivity (maximum bandwidth) although the listener might get the opposite impression because the interference and background noise increase when the selectivity is reduced so that the gross sound output becomes greater. However, the net carrier wave signal

output is less, as is also the effective sensitivity of the receiver.

When using the Transfilter, the gain is also negligibly affected as compared to the straight superhet gain. In practice, differences of a few decibels in over-all gain are readily compensated by adjustment of the receiver's gain control—provided, of course, the receiver has a proper margin of surplus amplification to start with. This should be true with any good receiver having a two-stage intermediate amplifier.

Of more importance than gain is the effective sensitivity of the receiver. This effective sensitivity is by no means a simple matter of how much amplification the receiver has. It is, rather, a matter of signal-noise ratio. It is best expressed in terms of the receiver's noise equivalent. The noise equivalent is the signal input required to give signal power output equal to the noise power output. The noise concerned is the receiver "hiss" noise, which would be the lowest possible noise background under ideal receiving conditions. The noise equivalent will be determined primarily by the signal-noise ratio at the input of the receiver but will be affected by the subsequent selectivity because the noise power output is generally reduced in proportion to the reduction in effective bandwidth of the receiver.

In tests which have been made with the filter system of my invention it has been observed that a considerable improvement was obtained upon increasing the selectivity. In the case of carrier wave reception with the crystal filter at maximum selectivity, for instance, the sensitivity is about 700 percent of the straight superheterodyne sensitivity, while the speech and music sensitivity with the Transfilter set for sharp band selectivity is raised to over 300 percent. The broad band selectivity adjustment of the crystal filter is likewise raised to over 300 percent.

In the range of adjustment of the selectivity or band-width control with these circuits, the resonance frequency of the crystal filter varies but a few cycles. This variation is so small that if the signal is first tuned in with the crystal set at maximum selectivity, the resonance frequency shift is not noticeable when the control is adjusted to the minimum selectivity point. With the Transfilter, the resonance frequency variation is a few hundred cycles at the most, although here again the variation is so small as to be hardly noticeable if the signal is first tuned in on resonance with the filter adjusted for maximum selectivity.

Referring now to Fig. 4, I show an arrangement whereby the selectivity may be adjusted by varying the resistance in the ground connection for the Transfilter. This arrangement including a potentiometer 29 provides an impedance matching circuit. When the resistance is entirely cut out the circuit is the same as shown in Fig. 1. In this position maximum selectivity is obtained if the condenser C_1 is adjusted for slightly higher capacitance than the resonance setting.

The impedance adjustment between the Transfilter and ground as shown in Fig. 5 is found to be suitable when the transformer secondary has a low impedance instead of the divided capacitance step-down arrangement used in Fig. 4. The circuit arrangement of Fig. 5 is, however, less flexible than that of Fig. 4 and, in fact, when used with a crystal filter in place of the Transfilter the circuit becomes one of the fixed selectivity type.

Fig. 6 shows a selectivity curve, the data for

which was plotted from tests made with the circuit arrangement shown in Fig. 4. The curves for zero resistance and for 2500 ohm resistance are not shown since they practically coincide with the 1000 ohm curve. The most interesting feature of these selectivity curves is the "notch" which appears with 20,000 ohm resistance. This double-hump effect indicates the equivalent of over-coupling with a transformer. As compared to the selectivity curves of Fig. 2, it is apparent that increased resistance tends to broaden the nose of the selectivity characteristic less effectively, while the skirts of the curves spread out more rapidly. They also show that the selectivity characteristic is generally less symmetrical with resistance variation than with variable impedance control. The curves of Fig. 7 show the total bandwidths for the various values of the resistance.

20 The gain of the circuit falls off somewhat more rapidly with increasing bandwidth as compared to the gain variation with impedance control of selectivity, although the loss is not especially noticeable in practice. On the whole, adjustable impedance control of selectivity appears to be preferable to resistance control with the Transfilter, just as it has been found to be preferable with the quartz crystal filter.

An interesting band-pass type of selectivity 25 characteristic was obtained with two similar Transfilter units connected in parallel in the circuit of Fig. 8. Except for the additional unit, the circuit is identical with that of Fig. 1. The two units had the same rated frequency of 465 30 kilocycles and actually differed only 200 cycles in resonance frequency. The band-pass curve of A of Fig. 9 was obtained with the band-width control condenser C₁ critically adjusted so that the same output was obtained on both "humps" 35 with constant signal input. The mid-frequency of this selectivity curve is approximately 1.2 kilocycles lower than the maximum-selectivity curve obtained with the input condenser C₁ adjusted for slightly greater capacitance than the 40 broad-band adjustment. The greater broadening of the selectivity curve near resonance is especially desirable in broadcast program reception, although the over-all carrier wave gain with this circuit is practically the same as with a single 45 unit.

50 Among other variations which I have tried, a particularly interesting one is use of a variable-selectivity Transfilter and a quartz crystal filter of the same type in cascade; that is, the crystal 55 filter circuit as the coupling element between the first detector and the first intermediate frequency amplifier, and the Transfilter as the coupling element between the first and second intermediate frequency amplifiers, provision being made to 60 switch either one in and out. A notable improvement with the Transfilter adjusted for medium selectivity is that the crystal filter selectivity characteristics are steepened in the skirts. While such cascade filters require fairly close tolerances 65 in the resonance frequencies of the Transfilter and crystal, there appears to be no great difficulty in meeting the requirements with production types. The fact that the Transfilter frequency 70 can be shifted over a range of a few hundred cycles, by tuning the input circuit above or below resonance, aids in accomplishing close alignment. Tests on three sample production-type Transfilter units have shown a maximum resonance-frequency difference of 380 cycles, the variation 75

being a plus or minus 200 cycles or less from the average.

Further interesting and useful selectivity characteristics are obtained with two variable-selectivity crystal filter circuits similarly in cascade. 5 With one filter adjusted for minimum selectivity and the other for optimum selectivity, for instance, independent rejection control in carrier wave reception makes it possible to eliminate two interfering heterodynes of different frequencies, 10 whether both are on the same side of resonance or on opposite sides of resonance. The crystals may differ 100 cycles or so in frequency without appreciably impairing operation, it has been found. In fact, such a difference actually may 15 prove advantageous, since it gives a band-pass characteristic in the region near resonance.

Fig. 9 shows maximum and minimum selectivity curves obtained with the band-pass filter circuit of Fig. 8. The mid-frequency of curve A 20 is approximately 1.2 kilocycles lower than the resonance frequency of curve B. Curve C is the straight superheterodyne selectivity curve without the filter. The selectivity curves are otherwise self-explanatory.

25 In carrying out my invention it will be apparent that various modifications may be made by those skilled in the art without departing from the spirit and scope of the invention itself. It is to be particularly understood that the curve 30 diagrams are in themselves merely exemplary of certain circuit arrangements and that where the values of different components in these circuits are varied, different curve diagrams would be produced. The practical application of the 35 invention will be particularly appreciated where systems of the type herein shown are adopted for short-wave reception and other amateur use. The scope of the invention is, however, by no 40 means limited in that manner.

I claim:

1. An electric wave filter system comprising a plurality of selectively operable band-pass circuits one of said circuits including a quartz piezo-electric device, another of said circuits including a mechanically resonant element in association with input and output piezo-electric elements of Rochelle salt, means including a variable impedance effectively in series with a selected one of said circuits for varying the frequency band width of said filter system, and means in shunt with said selected one of said circuits for applying thereto a phase displaced voltage whereby undesired signal frequencies are suppressed.

2. An intermediate frequency amplifier stage in combination with a filter system as defined in claim 1 and including switching means for selectively inserting a particular one of said band-pass circuits in series with said amplifier stage.

3. In an electric wave filter for a superheterodyne receiver, the method of varying the band-pass width and, conversely, the selectivity, which comprises feeding the energy to be filtered through one or another of several paths having different selectivity characteristics, the characteristic of one of said paths being due primarily to piezo-electric action, and the characteristic of another of said paths being due to a combination of mechanical resonance and piezo-electric 70 action, subjecting said energy to a series impedance, varying said impedance between a predominantly inductive and a predominantly capacitive value, thereby to tune the same on either side of the resonant frequency of said energy and 75

applying phase compensation in shunt with the operable one of said paths, thereby to suppress interfering signals of a frequency within the band width being filtered.

5. 4. An electric wave filter comprising an input circuit, an output circuit, circuit means comprising a selective electro-mechanical transducer having piezo-electric input and output coupling

elements for transferring energy from said input to said output circuits, a variable impedance effectively in series with said transducer for varying the frequency band width of the filter, and means for applying to said circuit means a voltage of controllable phase and value whereby undesired signal frequencies are suppressed.

JAMES J. LAMB.
